Patented Nov. 18, 1958

183,915

MOBILE MACHINE SHOP TRAILER

Kibbey W. Couse, Newark, N. J.

Application August 28, 1956, Serial No. 42,747

Term of patent 14 years

(Cl. D14—3)

Des. 183,915

PAGE 2

Des. 183,915

Figure 1 is a left side view of the mobile machine shop trailer, embodying my new design;

Figure 5 is a rear view.

I claim:

The ornamental design for a mobile machine shop trailer, as shown.
